PERCUSSION MUSICAL INSTRUMENT

Charles William Percy, London, England, assignor
to John E. Dallas and Sons Limited, London,
England

Application July 29, 1947, Serial No. 764,529
In Great Britain March 28, 1946

Section 1, Public Law 690, August 8, 1946
Patent expires March 28, 1966

10 Claims. (Cl. 84—422)

1

This invention relates to percussion musical instruments and to outfits comprising such instruments.

It has hitherto been the practice in bands, orchestras and the like to use a percussion musical outfit comprising a plurality of percussion instruments such as a bass drum, side drum, tympani, tom-toms, cymbals and the like, and it is an object of the present invention to provide an improved percussion musical instrument and an outfit comprising the same which is more compact, both in use and when packed for transport, and which consequently can be more easily used and more readily transported than the outfits previously proposed.

Thus according to the present invention there is provided a percussion musical instrument comprising a double vellum drum adapted to be supported with its axis in an upright or substantially upright position, foot-operated means for adjusting the tension of the upper vellum of the instrument during use so that tympano and tom-tom effects can be produced, and a foot-operated beater for striking the lower vellum of the drum to produce bass drum effects.

Further according to the invention there is provided a percussion musical outfit comprising a multi-purpose drum as set forth above and means associated with said drum for producing incidental effects, such as side drums, cymbals, cow bells and the like.

The tension of the upper vellum of the drum may be adjusted by means including an annular bearing member, for example mechanically as set forth in copending application Serial No. 649,910, British Patent No. 592,979, or hydraulically as set forth hereinunder and in British Patent No. 589,617, and the tension of the vellum may be maintained when the pedal for operating said means is released by means of wedge locking mechanism as set forth hereinunder and in British Patent No. 590,803.

The invention is illustrated by way of example in the accompanying drawings in which:

Figure 1 is a sectional side elevation of one construction of percussion musical instrument according to the invention;

Figure 2 is an enlarged view of a portion of the construction shown in Figure 1;

Figure 3 is a fragmentary side elevation of a percussion musical outfit according to the invention including mechanism according to British Patent No. 590,803 for maintaining the tension of the upper vellum of the drum;

Figure 4 is a perspective view of a double pedal

2

control for use in conjunction with the outfit of Figure 3;

Figure 5 is a front end view of the pedal control shown in Figure 4, and

Figure 6 is a perspective view of a percussion musical outfit including the double pedal control.

Figure 7 is a sectional side view of a modified construction embodying hydraulically operated mechanism for adjusting the tension of the upper vellum, and

Figure 8 is an inverted plan view of the mechanism for maintaining the tension of the upper vellum.

In the constructions shown in Figures 1 and 2, 15 the percussion musical instrument comprises a double vellum drum generally indicated at 10 having a cylindrical shell 11 of say 18 inches to 20 inches diameter and say 18 inches to 20 inches between its vellums, which is adjustably 20 mounted on four equally spaced supports 12 so that it may be arranged at the desired height in a vertical position as shown, by means of brackets 12'.

The tension of the upper vellum 13 is adapted 25 to be adjusted during use by foot-operated mechanism generally indicated at 14 so that the said vellum may be used for the production of tympano and tom-tom effects. A foot-operated beater, generally indicated at 15, is also provided 30 for striking the lower vellum 16 to produce bass drum effects. Additional effects can also be produced when the instrument is incorporated in an outfit as described hereinunder.

The foot-operated mechanism 14 for adjusting 35 the tension of the upper vellum 13 during use may be mechanically operated as shown, or hydraulically operated as described hereinunder and in British Patent No. 589,617, referred to above, and may act on the vellum either internally of the drum shell, as shown in the accompanying Figures 1 and 2, or externally thereof in known manner.

Means are also provided for adjusting the initial tension of the vellums. Thus the upper vellum 13 may be secured in a fixed position 45 over the upper end of the drum shell 11 by a captive hoop 17 so that its initial tension may be adjusted by means of a counter hoop 7 and screw rods 18 engaging with sockets 19 and clamps 19'. The lower vellum 16 may be secured in position 50 at the desired tension in a similar manner.

The foot-operated mechanism 14 for adjusting the tension of the upper vellum from within the instrument during use may comprise an annular bearing member 20, as described in copending

55

application Serial No. 649,910, now abandoned, and the said member 20 may be actuated by a series of levers 21, for example eight, pivotally mounted round the interior of the drum shell at equal distances apart. Each lever 21 may be in the form of a bellcrank lever which is pivoted at its elbow 22 to a supporting bracket 23 attached to the interior of the shell 11, one end 24 of the bellcrank lever being pivotally attached to a thrust rod 25 which engages the annular bearing member 20, while the other end 26 of the bellcrank lever is pivotally connected to a tension rod 27 extending downwardly towards the centre of the drum shell. The lower end of each tension rod 27 is attached to the socket plate 28 of a ball and socket joint or equivalent, the ball 29 of the joint being provided with a spring stem 30 which extends downwardly through a central aperture in the socket plate, forming the seating for the ball 29, and is connected to a transverse lever 31 between the ends thereof by a jointed rod 32. The lever 31 is disposed beneath the lower vellum 16, and the rod 32 extends downwardly through a central aperture 33 in the lower vellum 16, the peripheral edge of the said aperture being reinforced by a metal ring 34 riveted thereto as shown. The transverse lever 31 is pivoted at one end 35 to a supporting member 36 while its other end 37 serves as a foot tread.

By means of the vellum tensioning mechanism described above, the tension of the upper vellum 13 may be adjusted during the use to give either tympano effects or tom-tom effects, as desired, according to the tension applied to the vellum. The above described construction can conveniently be played by a standing player.

If desired the locking means described below and in British Patent No. 590,803 may be used instead of the simple lever 31 described above so that the tension on the vellum 13 may be maintained when the pressure on the foot tread is removed.

The foot-operated beater 15 for striking the lower vellum 16 may comprise a rod 38 which is provided with a striking head 39 at its forward end and is connected at its rear end to a pivoted foot tread 40 by means of a pair of interconnected links 41, 42, the rod 38 being pivotally mounted adjacent its rear end on a rod 43 which is mounted between two supporting legs 12 and secured to the outer end of the link 41 by a screw 41. Thus downward pressure on the foot tread 40 serves to rotate the rod 38 about the pivot pin 43 and thus moves the forward end of the rod upwardly to bring the beater head 39 into contact with the under surface of the lower vellum 16 to produce bass drum effects. The movement of the beater head away from the vellum under gravity may be supplemented by the pull of a tension spring 44. Any other form of foot-operated upwardly striking beater may of course be used.

In the percussion musical outfit shown in Figures 3 to 6, the above described simple lever construction for controlling the tension of the upper vellum is replaced by a modified construction in which the rod 32 previously referred to is operated by a Bowden cable mechanism with pedal control. In this construction, which is intended for use by a seated player, a double pedal control generally indicated at 45 with an enlarged heel plate 76 as shown, or a swivelling heel plate (not shown) may be used so that the player may use his left foot to control both the tension of the upper vellum of the drum and to operate a pair

of cymbals 46, 47 (known as "high-hat sock" cymbals).

The double foot control 45 shown more particularly in Figures 4 and 5 includes a pedal 48 for operating the cymbals 46, 47 through the Bowden cable mechanism, generally indicated at 49, and a second pedal 50 for operating the upper vellum 13 of the drum 10 through the Bowden cable mechanism generally indicated at 51. The 10 pedals 48 and 50 are pivoted at their rear ends to the common heel plate 76. At their front ends the pedals are connected to a base member 53 by rhombic linkages, generally indicated at 54 and 55 respectively. Thus linkage 54 for pedal 48 15 comprises four links 56, 57, 58 and 59, links 56 and 57 being pivoted at one end to the pedal 48 at the point 60, while the links 8 and 59 are pivoted at one end to the base member 53 at the point 61. The other ends of the links 56 and 58 20 are pivoted to the sheath 62 of the Bowden cable 63 while the other ends of the links 57 and 59 are pivotally connected to the end of the said cable 63. When the pedal 48 is depressed, the linkage 54 is elongated transversely causing the end of 25 the cable 63 to be drawn further out of the sheath 62 and thus lower the upper cymbal 46 into engagement with the lower cymbal 47 against the action of a helical compression spring (not shown) situated in the supporting column 67 of 30 the cymbals, the cymbal 46 being supported by a rod 68 attached to the Bowden cable. The column 67 may conveniently be connected to one of the supports 12 of the drum 10 by an arm 69 adjustably secured to said support.

35 In a similar manner, when the pedal 50 is depressed, link 55 is elongated transversely causing the end of the cable 65 to be drawn further out of the sheath 66 against the tension of the vellum 13, thus increasing the said tension, either 40 directly through rod 32 and the allied mechanism described above in connection with Figure 1, or indirectly through wedge locking means 79 indicated in Figures 3 and 8 and described below and in British Patent No. 590,803.

45 If desired the construction shown in Figures 3 to 6 may be used in combination with the construction shown in Figures 1 and 2, the rod 32 being connected by the lever 31 and also connected by Bowden cable mechanism to one of the 50 pedals of the above mentioned double pedal control so that the outfit may be played either by a seated player or by a standing player. The locking mechanism described below and in British Patent No. 590,803 may also be used in this combined construction.

A percussion musical outfit according to the invention may include a side drum 70 as shown in Figure 6, said drum being adjustably mounted on a supporting member 71 detachably associated 60 with the base member 53 of the pedals 48 and 50, and with the drum supports 12.

The drum 10 may also be provided with a straight or curved "trap" rail (not shown) for supporting cymbals, cow bells, wood blocks or the like. For example a curved trap rail may be supported by two of the supports 12 and extend round approximately a quarter of the circumference of the drum above the upper periphery thereof. A single cymbal may be adjustably 70 mounted in the upper end of one of the supports 12 if desired instead of on the trap rail.

It will of course be understood that the Bowden cable systems described above may be replaced by a chain or other connection. Furthermore it is to be understood that the invention is

not limited to the particular constructions described above. For example, instead of passing through the lower vellum 16, the rod 32 may be adjustably connected to the central part of a transverse lever which is pivoted at one end to a bracket on the interior of the drum shell while its other end may extend through a longitudinal slot in the drum shell for attachment by a wire cable to a foot tread so that downward pressure on the latter serves to draw the cable downward thus operating the transverse lever and in turn the tension rods 27 and consequently the bellcrank levers associated therewith to cause the thrust rods 25 to bear upwardly against the annular bearing member 20 and thus increase the tension on the vellum.

Instead of using a transverse lever which extends through a slot in the drum shell as described above, a lever may be used which is disposed wholly within the shell and is connected at its free end by a cable which passes under one pulley mounted within the shell and over another pulley mounted in a slot in the shell to the foot tread. Any stretch which may develop in the cable may be accommodated by adjustment of the connection between the above mentioned stem 30 and transverse lever. Instead of providing means for adjusting the tension of the vellum from within the instrument during use by means of an annular bearing member as described above, the vellum being positioned by a fixed or adjustable counterhoop, the vellum may be tensioned during use by means of an adjustable counterhoop which is slidably mounted on the outside of the shell of the drum and engages a captive vellum hoop as described in the above mentioned British Patent No. 590,803. Thus the counterhoop may cooperate with a plurality of rods equally spaced around the instrument, the lower end of each of which is connected to the outer end of a link which is pivoted to the exterior of the shell, the said links being in turn pivotally connected to the socket of the ball and socket joint or equivalent, previously referred to, by tension rods passing through the shell of the instrument.

As the further alternative, instead of using mechanical means for adjusting the tension of the upper vellum, the latter may be adjusted by fluid pressure arranged to act on the vellum from within the instrument or arranged to cooperate with the counterhoop as described in pending application Serial No. 649,910, now abandoned, British Patent No. 592,979, under the control of a foot tread as previously indicated.

Dampers may also be provided within the instrument in known manner for controlling the tone of the bass drum constituted by the lower vellum.

The tone of the lower vellum may be initially adjusted as indicated above or alternatively manually operable fluid or mechanical means as described in the above mentioned British patents may be provided for adjusting the initial tension of this vellum.

An elongated box, open at its upper end, may be attached in an inclined position to the exterior surface of the drum shell for holding the drum sticks, beaters and wire brushes. The space beneath the lower vellum which accommodates the beater may also be used to accommodate some of the incidental instruments during transport, and for this purpose an under tray may be provided if desired with brake controlled wheels or runners of known construction to facilitate the move-

ment of the outfit. Alternatively the supporting legs may be replaced by an annular skirt if desired.

It is to be understood that the construction shown in Figures 1 and 2 may be modified to include locking mechanism as described in British Patent No. 590,803, and that the construction shown in Figure 6 may be modified to include the separate pedal control 37 of Figure 1 and/or exclude the locking mechanism 65.

A construction in which the tension of the upper vellum is adjusted by hydraulically operated mechanism is shown in Figure 7 in which the fluid pressure means 80 comprise an annular pipe 81 secured by brackets 82 to the inner surface of the shell 11 so as to extend round the interior of the drum at a short distance from the upper vellum 13. The conduit 81 is formed with eight equidistantly spaced cylinder members 84 which communicate with the conduit and project therefrom towards the vellum parallel to the axis of the drum.

Each of the cylinder members 84 is fitted internally with a piston member comprising a piston head within the cylinder member and a rod 87 which is attached to the said piston head and extends through a liquid-tight packing member 88, the latter being screwed on to the free end of the cylinder member 84. The outer end of each rod 87 engages in a socket 91 in an annular bearing member 92 which makes contact with the interior surface of the vellum 13, the inturned end portion 93 of the shell 11 being cut away as shown to accommodate the said sockets 91.

The annular conduit 81 is also provided with a portion 94 which extends through the shell 11 of the drum adjacent the lower end thereof, the lower end of said portion communicating with a foot operated control member in the form of a fluid pressure cylinder 95 with a piston 83 which is adapted to be depressed within the cylinder 95 by means of the foot-tread 37 on the transverse lever 31.

The conduit 81, the portion 94, the cylinder members 84 and the pressure cylinder 95 are charged with a pressure-transmitting fluid, for example, thick grease, so that when pressure is applied to the pressure fluid by depressing the foot tread 37, the piston members in the cylinder members 84 are caused to press the annular bearing member 92 against the vellum 13 and thus increase the tension on the latter.

The wedge locking mechanism 79 indicated in Figure 3 is illustrated in detail in Figure 8 which is an inverted plan view thereof. As shown in Figure 7 this mechanism includes motion transmitting mechanism 108 which is arranged within a casing and is connected with the vellum tensioning mechanism within the drum by means of a rod 114, corresponding with the rod 32 previously described with reference to Figure 1, the said rod 114 extending through an upwardly projecting portion at one end of the casing and through a central aperture in the lower vellum.

The spindle 114 is connected at its lower end to one end of a short length of chain 115 which passes partly round a toothed jockey pulley 116. The other end of the chain 115 is connected to a friction locking device generally indicated at 117 which is in turn connected by a road 118 to the cable 65 of the Bowden mechanism 49.

The locking device 117 comprises a wedge member 122 with flat side surfaces 123 which converge towards the chain 115, and two slide mem-

bers 124 with inclined surfaces 125 between which the wedge member is disposed, the surfaces 123 being arranged parallel to and adapted to co-operate with the corresponding inclined surfaces 125. The slide members 124 are in turn arranged between parallel supporting guides 126 secured to the interior surface of the middle portion of the casing.

The surfaces 123 and 125 are grooved longitudinally to form races for balls 127 for facilitating the sliding movement between the members 122 and 124 during locking and unlocking as described hereinunder.

The wedge member 122 is provided at its wider end with a stem 128 and bears at its other end against a transverse abutment member 129, and the members 122 and 129 are disposed between two transverse bars 130 and 131, the bar 130 being attached to the adjacent end of the chain 115 and the bar 131 being screwed on to the adjacent end of the rod 118. The outer ends of the bars 130 and 131 are connected by rods 132 which extend through longitudinal apertures in the slide members 124, the apertures in the members 124 being large enough to allow the necessary play on the rods 132 during the operation of the device. The ends of the rods 132 are screw-threaded to receive nuts 133 so that the wedge member 122 and the abutment member 129 can be clamped together between the transverse bars 130 and 131, the member 129 being spaced a short distance from the adjacent ends of the members 124 when the parts of the device are in their locked position.

To enable the position of the slide members 124 to be adjusted relative to the wedge member 122 when under vellum tension, lock nuts 134 which limit the rearward movement of the slide members relative to the wedge member are screw-threaded onto the rods 132, the correct functioning of the device being dependent on the setting of the nuts 134. When the parts of the device are in their locking position the slide members bear against the nuts 134.

The parts of the locking device are normally covered by a plate (not shown) which is attached by screws 154 to the guides 126.

When in locked position the wedge member occupies a position relative to the slide members as shown in Figure 8. When a pull is exerted on the wedge member 122 by the foot tread, the wedge member 122 is loosened between the slide members 124, and the member 129 is caused to abut against the adjacent ends of the members 124 so that if the pull continues to be exerted the wedge and slide members are moved as a whole to the right relative to the guides 126 to increase the tension of the vellum. When the pull ceases the tension of the vellum serves to reverse the movement of the wedge member 122 either to lock the slide members 124 against the guides 126 and thus maintain the tension of the vellum, or to allow the wedge and slide members to return as a whole to the left relative to the guides 126 to permit the vellum to assume a reduced tension, the locking or the reverse movement being effected according to the manner in which the pedal is released. If the pressure on the foot tread is removed so as to allow the wedge member 122 to coonerate sharply with the slide members 124 under the unrestrained action of the vellum tension, the slide members 124 are automatically locked against the guides 126, but if the wedge member is only allowed to bear gently against

said members 124, the tension of the vellum being largely restrained by the pressure on the pedal after the wedge member has been released, the slide members are caused to slide in the guides 126 to reduce the vellum tension.

What I claim is:

1. A percussion musical instrument comprising a double vellum drum adapted to be supported with its central longitudinal axis in an upright or substantially upright position, foot-operated means for adjusting the tension of the upper vellum of the instrument during use so that tympano and tom-tom effects can be produced, and a foot-operated beater for striking the lower vellum of the drum to produce bass drum effects.

2. A percussion musical instrument as claimed in claim 1, wherein the foot-operated means for adjusting the tension of the upper vellum of the instrument include an annular bearing member within the drum shell, lever mechanism for pressing said member against the under surface of said vellum, and a single control pedal for operating said mechanism.

3. A percussion musical instrument as claimed in claim 1, wherein the foot-operated means for adjusting the tension of the upper vellum of the instrument include an annular bearing member within the drum shell, lever mechanism for pressing said member against the under surface of said vellum, a single control pedal for operating said lever mechanism and a tension rod connected to said mechanism, said rod passing through a central aperture in the lower vellum of the drum.

4. A percussion musical instrument as claimed in claim 1, wherein the foot-operated means for adjusting the tension of the upper vellum of the instrument include an annular bearing member within the drum shell, lever mechanism for pressing said member against the under surface of said vellum, a single control pedal for operating said lever mechanism, a tension rod connected to said mechanism, said rod passing through a central aperture in the lower vellum of the drum, and the peripheral edge of the aperture being reinforced by a flat metal ring.

5. A percussion musical instrument as claimed in claim 1, wherein the foot-operated means for adjusting the tension of the upper vellum of the instrument include an annular bearing member within the drum shell, lever mechanism for pressing said member against the under surface of said vellum, a single control pedal for operating said lever mechanism, a tension rod connected to said mechanism, said rod passing through a central aperture in the lower vellum of the drum, and the peripheral edge of the aperture being reinforced by a flat metal ring, and wherein the lever mechanism includes a plurality of levers, pivotally arranged equidistantly around the interior of the drum shell adjacent the upper end thereof, one end of each lever being connected to the annular bearing member by a thrust rod, while the other end of each lever is connected by the tension rod which extends towards the center of the drum and is connected to the socket member of a ball and socket joint carried by the tension rod connected to the operating pedal.

6. A percussion musical instrument comprising a double vellum drum adapted to be supported with its central longitudinal axis in an upright or substantially upright position, foot-operated hydraulic means for adjusting the tension of the upper vellum of the instrument during use so that tympano and tom-tom effects can be produced, and a foot-operated beater for striking

the lower vellum of the drum to produce bass drum effects.

7. A percussion musical instrument comprising a double vellum drum adapted to be supported with its central longitudinal axis in an upright or substantially upright position, foot-operated lever mechanism extending through the shell of the drum, for adjusting the tension of the upper vellum of the instrument during use so that tympano and tom-tom effects can be produced, and a foot-operated beater for striking the lower vellum of the drum to produce bass drum effects.

8. A percussion musical instrument comprising a double vellum drum adapted to be supported with its central longitudinal axis in an upright or substantially upright position, foot-operated means for adjusting the tension of the upper vellum of the instrument during use so that tympano and tom-tom effects can be produced, and a foot-operated beater for striking the lower vellum of the drum to produce bass drum effects, and separate means for enabling the tension of the upper and lower vellums to be initially adjusted.

9. A percussion musical instrument as claimed in claim 1, wherein the foot-operated means for adjusting the tension of the upper vellum of the instrument include an annular bearing member

5

within the drum shell, lever mechanism for pressing said member against the under surface of said vellum, and a single control pedal for operating said lever mechanism, by means extending through the shell of the drum.

10. A percussion musical instrument comprising a double vellum drum adapted to be supported with its central longitudinal axis in an upright or substantially upright position, foot-operated means for adjusting the tension of the upper vellum of the instrument during use so that tympano and tom-tom effects can be produced, said means including wedge locking mechanism so that the tension of said upper vellum may be maintained when the pedal is released, and a foot-operated beater for striking the lower vellum of the drum to produce bass drum effects.
